UNITED STATES PATENT OFFICE.

WALLACE L. CLAY, OF THE UNITED STATES ARMY.

ARMOR-PIERCING AND TRACER BULLET.

Application filed November 18, 1918. Serial No. 263,049.

(FILED UNDER THE ACT OF MARCH 3, 1883, 22 STAT. L., 625.)

To all whom it may concern:

Be it known that I, WALLACE L. CLAY, lieut. col. Ordnance Department, United States Army, a citizen of the United States, 5 stationed at Frankford Arsenal, have invented an Improvement in Armor-Piercing and Tracer Bullets, of which the following is a specification.

The invention described herein may be 10 used by the Government, or any of its officers or employees in prosecution of work for the Government, or by any other person in the United States, without payment of any royalty thereon.

15 This invention relates to devices commonly known as combined tracer and armor piercing bullets or projectiles and capable of emitting a pencil of visible vapor by day or a pencil of light by night to denote the line 20 of flight, and to pierce the objective, and has for one of its objectives to improve and simplify the construction and increase the efficiency of devices of this character.

Another object of the invention is to provide 25 a device of this character having means whereby the vapor and light producing composition is protected during the flight of the projectile and the emanations controlled and directed.

30 Another object of the invention, is to produce a device of this character having means whereby the container for the vapor and light producing medium is secured to the body of the projectile.

35 With these and other objects in view the invention consists in certain new and useful improvements hereinafter described and specifically set forth in the claims, and in the drawings illustrative of the preferred 40 embodiment of the invention—

Fig. 1 is a longitudinal section of the improved projectile.

Fig. 2 is a longitudinal section of the jacket or shell.

45 Fig. 3 is a longitudinal section of the receptacle for the tracer composition.

Fig. 4 is a detached side elevation of the slug.

50 The improved device comprises a core or slug 10 pointed at the forward end and encased in a jacket or shell 11.

The slug is formed of an armor piercing metal such as steel, while the shell or jacket is of a metal or metallic compound which will rupture upon impact with an objective 55 such as an armor plate, engine body or frame or other resisting structures leaving the slug free to penetrate the resisting body. The metal of the jacket may be cupro-nickel, gilding metal or the like which is readily 60 rupturable when striking an objective or hard body.

Located within the shell rearwardly of the slug is a receptacle 12 for a tracer composition, indicated at 13.

65 The receptacle 12 has its inner end closed and slightly curved and resting against the base of the slug so as to hold the slug firmly against rearward movement.

The receptacle 12 is open at the rear end 70 and secured in position by "crimping" the rear end of the shell inwardly as shown in Fig. 1.

The "charge" 13 of the receptacle may be inserted before or after the deposit in the 75 shell of the casing 12.

The action of the projectile is as follows: When the cartridge is fired, the flame from the propelling powder ignites the tracer composition, which burns throughout the 80 flight of the projectile approximately 300 or 400 yards or longer, depending upon the tracer composition used. Upon impact with the enemy's armor plate, engine parts, or any other resisting material, the jacket is 85 ruptured while the steel plug causes penetration.

What is claimed as new and desired to secure by Letters Patent is:

1. A projectile of the class described comprising a jacket of a material ruptured upon impact, an armor piercing slug within the forward portion of the jacket, and a receptacle within the jacket formed with the curved closed end resting against the base of the 95 slug, said receptacle containing a substance for producing a visible vapor and a flash of light.

2. A projectile of the class described comprising a jacket of a material ruptured upon 100 impact, an armor piercing slug within the forward portion of the jacket, a receptacle

within the jacket having a closed end resting against the base of the slug, said receptacle containing a substance for producing a visible vapor and a flash of light, and means 5 for holding the receptacle within the jacket.

3. A projectile of the class described comprising a jacket of a material ruptured upon

impact, an armor piercing slug within the forward portion of the jacket, and a receptacle within the jacket closed at the inner end 10 and bearing thereby against the slug, said receptacle containing a substance for producing a visible vapor and a flash of light.

WALLACE L. CLAY.
